UNITED STATES PATENT OFFICE.

EDWARD A. SCHREIBER, OF CHICAGO, ILLINOIS, ASSIGNOR TO EGBERT H. GOLD, OF CHICAGO, ILLINOIS.

WATER SYSTEM FOR RAILWAY PASSENGER CARS.

1,249,518.

Specification of Letters Patent. Patented Dec. 11, 1917.

Application filed April 9, 1917. Serial No. 160,746.

To all whom it may concern:

Be it known that I, EDWARD A. SCHREIBER, a citizen of the United States, residing at Chicago, in the county of Cook and State of Illinois, have invented certain new and useful Improvements in Water Systems for Railway Passenger Cars, of which the following is a specification.

My invention relates to certain improvements in the water systems used on railway passenger cars, the purpose of the improvements being to prevent exposed portions of the apparatus from freezing in extremely cold weather. According to the usual practice, sleeping cars, and railway cars of that general type, are furnished with a water supply tank, usually carried underneath the car, from which water is forced by air pressure, taken from the air brake line of the train, to the faucets and other water fixtures in the car. The supply tank is commonly provided with filling means comprising a filling pipe and a drip pipe. This construction is standard on most railroads and need not be described except so far as concerns the present improvements. There may be other drip or discharge pipes, for example, the waste pipes from the toilet room wash bowls. These drip pipes are peculiarly likely to be frozen up in cold weather because the outflow of water through them is intermittent and in small quantities. There is also some danger of the water being trapped and frozen in the supply tank filling pipe. The necessity of stopping the train for the purpose of thawing out these pipes is a very common cause for the failure of railway trains to make their schedules during the winter months.

The present invention seeks to provide certain arrangements whereby steam taken from the steam train line, and automatically controlled to prevent wastage, is employed for keeping the exposed parts of the water system above mentioned warm enough so that the danger of a freeze up is obviated.

The invention is illustrated, in certain preferred embodiments, in the accompanying drawings wherein—

Figure 1 is a plan view, with certain parts in section, of the water supply tank for a sleeping car, or car of that type, and associated apparatus, showing the improvements of my invention applied thereto.

Fig. 2 is an end elevation of this apparatus, certain parts also being shown in section.

Fig. 3 is a vertical sectional view of the discharge end of the supply tank drip pipe showing the means employed for preventing the same from being clogged with ice.

Fig. 4 is a sectional plan on line 4—4 of Fig. 3.

Fig. 5 is a fragmentary vertical sectional view illustrating one of the wash bowls in the toilet room of the car and its drip pipe, and means for protecting the latter from freezing.

Fig. 6 is a plan view of the branch pipe and fitting forming part of said means; and

Fig. 7 is a sectional view, on an enlarged scale, taken on line 7—7 of Fig. 6.

Like characters of reference designate like parts in the several figures of the drawings.

Referring first to Figs. 1 to 4 inclusive, 10 is the water supply tank which is suitably supported in a sheet steel box 11 having an insulating lining 12, the box being secured to the under side of the flooring 13 of the car. 14 is the usual filling pipe for the tank 80 and 15 is the drip pipe. A branch pipe 16 extends from the steam train line 17 and entering the box 11 passes around the supply tank 11, as indicated at 16^a; thence along close to the filling pipe 14, as indicated at 16^b, thence to a fitting 18, this portion of the pipe being indicated at 16^c, and from the fitting to the thermostat end of a vapor regulator 19, this portion of the branch pipe being designated 16^d. The vapor regulator 90 may be of any suitable well-known type and is arranged so as to automatically control the flow of steam through the branch pipe. Preferably a shut-off valve 20 is arranged in pipe 16 between the train line and the vapor regulator. 21 is a tubular insulating covering surrounding the filling pipe 14 and length 16^b of the heating pipe. The fitting 18 (Figs. 3 and 4) comprises a casing formed with a centrally arranged sleeve or cylindrical web 22 through which the lower end of the drip pipe 15 extends, preferably with a slidable relation thereto so as to permit expansion and contraction of the drip pipe.

The web 22, being exposed to steam passing 105 through the ports 23 of the fitting from pipe length 16^c to the length designated 16^d, is kept warm and imparts enough warmth to

the drip pipe to prevent the same from freezing up. The vapor regulator operates to admit just enough steam to the heating pipe 16 to compensate for condensation losses 5 without wastage.

In Figs. 5 to 7 inclusive, I have shown, as applied to the wash bowl waste pipe, a fitting and connections, for the purpose of keeping the waste pipe free of ice, similar 20 to the arrangements just described in connection with the drip pipe of the supply tank. The wash bowl is indicated at 24 and its waste pipe at 25. The latter projects down through the flooring 13 of the car, the lower end extending into a sleeve or cylindrical web 26 forming part of a fitting 27. This fitting is interposed in a pipe 28 connected with a train line 17, the return end of which, 29, is connected to the inlet end by 20 a union 30; this arrangement does not require a vapor regulator, as the amount of condensation is relatively small. The fitting 27 is formed with a boss 31 providing space for a packing 32, the packing being held in 25 place by the nut 33.

I claim:

1. In combination with a steam train line and water supply tank of a railway car, a filling pipe for said tank, a branch pipe from said train line, a portion of which lies along and adjacent said filling pipe, and means for automatically controlling the flow of steam through said branch pipe so as to keep the filling pipe warm without wastage 35 of steam.
2. In combination with a steam train line and water supply tank of a railway car, a filling pipe for said tank, a branch pipe from said train line which extends around 40 the tank and a portion of which lies along and adjacent to said filling pipe, and means for automatically controlling the flow of steam through said branch pipe so as to keep said tank and filling pipe warm without 45 wastage of steam.
3. In combination with a steam train line and water supply tank of a railway car, a filling pipe for said tank, a branch pipe from said train line which extends around 50 the tank and a portion of which lies along and adjacent to said filling pipe, means for automatically controlling the flow of steam through said branch pipe so as to keep said tank and filling pipe warm without wastage 55 of steam, an insulated box which surrounds said tank, and a tubular insulating covering for the filling pipe and the portion of the branch pipe lying adjacent thereto, said tubular covering having an open end 60 through which the upper end of the filling pipe extends.

4. In combination with the steam train line of a railway car and the water supply tank thereof provided with a drip pipe; and a branch pipe from the train line provided 65 with a fitting embracing the lower end of said drip pipe through which fitting steam is adapted to pass and means for automatically controlling the flow of steam through said branch pipe to keep the drip pipe from 70 freezing.

5. In combination with the steam train line of a railway car and the water supply tank thereof provided with a drip pipe, a branch pipe from the train line, and a fitting 75 in said branch pipe formed with a steam port and with a sleeve arranged in said steam port through which the drip pipe extends slidably and means for automatically controlling the flow of steam 80 through said branch pipe so as to prevent clogging of said pipe without wastage of steam.

6. In combination with the steam train line of a railway car and the water supply 85 tank thereof provided with a filling pipe and with a drip pipe, a fitting embracing the lower end of said drip pipe and provided with a steam port, and a branch pipe adapted to extend around said tank, a portion 90 of which lies along adjacent said filling pipe and a portion of which is arranged to supply steam to said fitting.

7. In combination with the steam train line of a railway car and the water supply 95 tank thereof provided with a filling pipe and with a drip pipe, a fitting embracing the lower end of said drip pipe and provided with a steam port, a branch pipe adapted to extend around said tank, a portion of 100 which lies along adjacent said filling pipe and a portion of which is arranged to supply steam to said fitting, and means for automatically controlling the flow of steam through said branch pipe.

8. In combination with the steam train line of a railway car and the water supply tank thereof provided with a filling pipe and with a drip pipe, a fitting embracing the lower end of said drip pipe and provided with a steam port, a branch pipe adapted to extend around said tank, a portion 110 of which lies along adjacent said filling pipe and a portion of which is arranged to supply steam to said fitting, means for automatically controlling the flow of steam through said branch pipe, an insulated box surrounding said tank, and a tubular insulating covering which surrounds the filling pipe and the portion of the branch pipe 115 lying adjacent thereto.

EDWARD A. SCHREIBER.
